Attorney.

UNITED STATES PATENT OFFICE.

EMIL BÖSEBECK, OF BARMEN, GERMANY, ASSIGNOR TO MAX HENKELS, OF NEW YORK, N. Y.

MACHINE-BRAIDED LACE.

Application filed June 5, 1924. Serial No. 718,026.

To all whom it may concern:

Be it known that I, EMIL BÖSEBECK, a citizen of the German Empire, residing at Barmen, Rhenish Prussia, Germany, have 5 invented certain new and useful Improvements in Machine-Braided Lace, for which I have filed an application for patent in Germany, on June 4, 1923, and of which the following is a specification.

10 The invention relates to that type of lace which is manufactured on the so-called single-thread lace-braiding machine, that is on a machine of the type generally described in British Patent No. 11,411 of 1894 to 15 Malhère, and which has leaf-like figures which are arranged in gaps or meshes in the lace-ground and are situated at right angles to the longitudinal direction of the lace and are connected with the remaining portions of 20 the lace only at their two ends.

In manufacturing such lace by mechanical means the method adopted hitherto, similar to that in hand-braiding has been this, that the leaf-like figures or leaflets, arranged 25 first of all with their longitudinal axes parallel to the longitudinal direction of the lace, are formed with the aid of a plurality of threads led out from the ground or the remaining portions of the lace and running 30 partly in the longitudinal direction of the figure, and partly in the transverse direction thereto, and are then set at right-angles to the longitudinal direction of the lace, whereupon the threads forming the figures are 35 again worked into the ground or into the remaining portions of the lace. This mode of operation is tedious and time-absorbing because, on the one hand, the figure must be worked in the direction of its longitudinal 40 axis and during this time the work on the remaining portions of the lace must be stopped, and on the other hand, after the completion of the figure, the fabric must be moved backwards in order to place the figure 45 transversely. This requires moreover a long jacquard card and draw-off mechanism arranged in a special manner with an upwardly and downwardly movable mandril.

According to the invention the manufacture 50 of leaf-like figures which are situated with their longitudinal axes at right-angles to the longitudinal direction of the lace and are arranged in gaps or meshes in the ground and which are connected only at their ends 55 with the other portions of the lace is very

considerably simplified, in that these figures consist of a plurality of threads which are arranged in the form of arches and each of which enters into the figure at one end of the latter and passes out again at the same end, 60 and of a plurality of threads running to and fro in the figure in the longitudinal direction of the latter, which threads are bound in the manner of weft with the arched threads. The latter threads can be secured 65 in position in part by means of crossings between them of the threads running to-and-fro in the longitudinal direction, and in part by means of the return-loops formed by the latter threads. In order to obtain leaflets 70 with pointed ends, the threads running to-and-fro in the longitudinal direction of the figure extend preferably only in the middle of the figure throughout its entire length, whereas at the sides of the figure they extend over only a portion of the length of the latter. 75

By the new construction of leaflet arranged with its longitudinal axis at right angles to the longitudinal direction of the lace the manufacture of lace having such figures is rendered more economical than heretofore, since, on the one hand, during the formation of the figure, the production of the remaining portions of the lace need not be 80 interrupted, the figure being able to be produced simultaneously with those portions of the lace which, viewed laterally, lie adjacent to the same, and since on the other hand, the figure from the first takes its appointed position in the lace and is consequently worked 85 in the direction of its short axis, whereby at the same time the jacquard-card is very considerably shortened, and because finally 90 since the lace can be drawn off in the usual manner even during the production of the figures situated at right angles to the longitudinal direction of the lace, a special construction of draw-off mechanism is no longer 95 required. 100

One embodiment of the invention is illustrated by way of example in the accompanying drawing, wherein

Fig. 1 shows a piece of the lace at about actual size, and

Fig. 2 a fragment of the lace on a much enlarged scale.

The embodiment shown is a lace insertion with parallel longitudinal edges 1, 2 the wide-meshed ground of which lace is formed 110

of braided-strips 3. The main pattern of the lace consists of leaf-like figures 4, 5, 6, 7, 8, 9, 10, 11 which in each instance are arranged in groups of eight figures in the form 5 of the spokes of a wheel and are surrounded by a braided ring 12, so that together with the latter they represent a wheel. The Figures 4, 8 situated with their longitudinal axis parallel to the longitudinal direction of 10 the lace as well as the Figures 5, 7, and 9, 11 situated with their longitudinal axis in a diagonal direction are formed in the usual manner, that is, they consist each of three threads *a*, *b*, *c* running in the longitudinal 15 direction of the figures and of a fourth thread *d* which is passed to and fro between the longitudinal threads *a*, *b*, *c* transversely with respect to the figure and is braided with these threads. See especially the right of 20 Fig. 2.

The Figures 6, 10 situated with their longitudinal axis at right angles to the longitudinal direction of the lace are, however, formed in a novel manner. As the middle 25 of Fig. 2 particularly shows, they consist according to the invention of, for example, four threads *f*, *g*, *h*, *i* arranged in the form of arches and of, for example, two threads *k*, *m* conducted to-and-fro in the longitudinal 30 direction of the leaflet. Half of the arched threads are led into the figure at one of its ends and half of them at its other end and each arched thread leaves the figure again at the end at which it entered. Thus 35 the threads *f*, *g* enter the figure at the inner end of the same in order to leave it again also at the inner end, while the threads *h*, *i* enter and leave at the outer end. The threads *k*, *m* running to-and-fro in the longitudinal 40 direction may, on the other hand, all enter the figure at the inner end thereof and also leave the same again at this end. The threads *k*, *m*, which run to-and-fro, are connected in the manner of weft with the arched threads *f*, *g*, *h*, *i* and at places, for 45 example at *n* and *o*, cross one another between two arched threads. Owing to these intercrossings as well as owing in part to the return-loops of the threads *k*, *m* the arched threads *f*, *g*, *h*, *i* are secured in position in 50 the figure so that they cannot be displaced therein.

In order to give the figure at its ends as pointed a shape as possible, that is, to give it 55 the proper form of a leaflet, the threads *k*, *m* are led to-and-fro in the middle of the figure throughout its entire length, while at the sides of the figure they extend only over a portion of the length of the figure. In the 60 embodiment shown the outer end of the leaflet is made pointed or tapered in this manner. Obviously the arrangement may be such that the figure is pointed at both ends. In this case if necessary the threads *k*, *m* 65 running to-and-fro in the longitudinal direc-

tion of the figure instead of both entering the figure at the inner end may in part enter at the outer end and leave it again at the outer end.

Of course many modifications of the embodiment shown are possible without affecting the essence of the invention. In particular, the number of the arched threads and of the threads which run to-and-fro may differ from the number shown. 75

I claim:

1. Method of producing braided lace wherein open spaces are filled with leaf-like patterns, the leaves extending in a direction substantially perpendicular to the longitudinal axis of the lace, which method comprises the arranging of sets of threads with arch-shaped sections within said open spaces, entering and leaving the leaves at one and the same end, and interbraiding 80 said arch sections in a weft-like manner with transversal threads, the latter running substantially at right angles thereto. 85

2. Method of producing braided lace wherein open spaces are filled with leaf-like 90 patterns, the leaves extending in a direction substantially perpendicular to the longitudinal axis of the lace, which method comprises the arranging of sets of threads with arch-shaped sections within said open spaces, entering and leaving the leaves at one and the same end, and interbraiding 95 said arch sections in a weft-like manner with transversal threads, the latter running substantially at right angles thereto and crossing 100 each other so as to interlock the arch-sections in their relative position.

3. Method of producing braided lace wherein open spaces are filled with leaf-like 105 patterns, the leaves extending in a direction substantially perpendicular to the longitudinal axis of the lace, which method comprises the arranging of sets of threads with arch-shaped sections within said open spaces, entering and leaving the leaves at one and the same end, and interbraiding 110 said arch sections in a weft-like manner with transversal threads, the latter running substantially at right angles thereto and being interbraided with the entire set 115 of arch sections at the central part of the leaves, but engaging only part of said arch sections near the edges of the leaves.

4. Braided lace having open spaces filled 120 with leaf-like patterns, the leaves extending in a direction substantially perpendicular to the main axis of the lace, and comprising arch-shaped sections of threads which enter and leave the leaves at one and the same end, and transversal threads running substantially at right angles thereto, said transversal threads being interbraided in a weft-like manner with the arch sections. 125

5. Braided lace having open spaces filled 130 with leaf-like patterns, the leaves extending

in a direction substantially perpendicular to the main axis of the lace, and comprising arch-shaped sections of threads which enter and leave the leaves at one and the same 5 end, and transverse threads running substantially at right angles thereto, said transversal threads being interbraided in a weft-like manner with said arch sections and crossing each other so as to interlock the arch 10 sections in their relative position.

6. Braided lace having open spaces filled with leaf-like patterns, the leaves extending in a direction substantially perpendicular to

the main axis of the lace and comprising arch-shaped sections of threads which enter and leave the leaves at one and the same end, 15 and transverse threads running substantially at right angles thereto, said transversal threads being interbraided in a weft-like manner with said arch sections at the central part of said leaves but engaging only part of said arch sections near the edges of the leaves.

In testimony whereof I affix my signature.

EMIL BÖSEBECK.
